(57) **CLAIM**

The ornamental design for the battery, as shown and described.

DESCRIPTION

FIG. 1 is a top perspective view of the battery of the invention;

FIG. 2 is a top plan view of FIG. 1;

FIG. 3 is a right side elevation view of FIG. 1; the opposite side being a mirror image thereof;

FIG. 4 is a front end view FIG. 1; and,

FIG. 5 is a rear end view of FIG. 1.

The broken line disclosure of unclaimed environmental structure shown in the drawings is for illustrative purposes only and does not constitute a part of the claimed design.
